ATTORNEY

UNITED STATES PATENT OFFICE.

FREDERICK A. C. KAISER, OF HOBOKEN, NEW JERSEY.

DESIGN FOR A CIGAR-BAND.

• No. 39,261.

Specification for Design.

Patented April 14, 1908.

Application filed February 6, 1908. Serial No. 414,657. Term of patent 7 years.

To all whom it may concern:

Be it known that I, FREDERICK A. C. KAISER, a citizen of the United States, residing at 1020 Hudson street, Hoboken, in the county of Hudson and State of New Jersey, have invented a new, original, and ornamental Design for Cigar-Bands, of which the following is a specification, reference being had to the accompanying drawing, forming a part thereof.

The figure is a plan view of my original band showing my new design.

I claim

The ornamental design for a cigar band as shown.

FREDERICK A. C. KAISER.

Witnessses:

JOSEPH C. RUFENACHT,
FREDK. L. MENDEL.
